[57] CLAIM

The ornamental design for a rebounder for a basketball goal, as shown and described.

DESCRIPTION

FIG. 1 is a front elevational view of the rebounder for a basketball goal showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view with a basketball goal shown in broken lines for illustrative purposes only that form no part of my design; and,

FIG. 8 is a left elevational view of FIG. 7.

FIG. 1

FIG. 2

*FIG. 3**FIG. 4**FIG. 5*

FIG. 6

FIG. 7

FIG. 8
